poration of Illinois

Application July 2, 1932, Serial No. 620,580

27 Claims. (Cl. 270—22)

The present invention relates to printing presses and more particularly to a novel and improved bed and cylinder printing press and folder therefor.

5 Objects and advantages of the invention will be set forth in part hereinafter and in part will be obvious herefrom, or may be learned by practice with the invention, the same being realized and attained by means of the instrumentalities and 10 combinations pointed out in the appended claims.

The invention consists in the novel parts, constructions, arrangements, combinations and improvements herein shown and described.

The accompanying drawings, referred to herein 15 and constituting a part hereof, illustrate one embodiment of the invention, and together with the description, serve to explain the principles of the invention.

The accompanying drawings illustrate a typical 20 embodiment of the present invention, and in these drawings, the details of many of the conventional parts and elements have been omitted for the sake of clearness. Of the drawings:

Fig. 1 is a diagrammatic vertical section, taken 25 longitudinally of the present embodiment of the invention;

Fig. 2 is a diagrammatic plan view showing one 30 path of the web in passing through the press;

Fig. 3 is a similar diagrammatic view showing 35 an alternative path for the web in passing through the press;

Fig. 4 is a detailed fragmentary side elevation 40 of the rewinding and web roll storing mechanism;

Fig. 5 is a diagrammatic, fragmentary, sec- 45 tional view illustrating the operation of the em- bodiment and showing the association of two pre- viously printed webs with a third web being print- ed and delivered by the press;

Fig. 6 is a fragmentary side elevation of the web 50 tension controlling mechanism for maintaining the web tension substantially constant;

Fig. 7 is a plan of the parts illustrated in 55 Fig. 6;

Fig. 8 is a fragmentary side elevation, with cer- 60 tain parts broken away, of an equalizing mech- anism in accordance with the present invention for rendering constant the speed at which the web is fed to a bed and cylinder press from the web roll and delivered from the press;

Fig. 9 is a diagrammatic, vertical and longi- 65 tudinal section illustrating the position of the parts during the removal or positioning of plates 55 on the press bed;

Fig. 10 is a detailed side elevation of a feeding and cutting cylinder;

Figure 11 is a side elevation, partially diagram- 70 matic, of the driving unit; and

Figure 12 is a plan view of the mechanism 5 shown in Figure 11.

The present invention has for some of its prin- 10 cipal objects the provision of a novel and im- proved bed and cylinder printing press for print- ing a web of paper in multi-color or alternatively 15 for perfecting a web of paper; the provision of a novel and improved bed and cylinder printing press for the alternative production of an un- usually large variety of products; the provision 20 of an improved bed and cylinder printing press 15 of simplified construction, permitting easy ac- 25 cess to all parts thereof; and, the provision of a novel and improved folding mechanism.

Further objects of the invention are the pro- 30 vision of an improved web tension controlling 20 mechanism for bed and cylinder printing presses, improved means for maintaining the speed of the web roll and delivery constant as the web is passed 25 through a bed and cylinder press, an improved means for rewinding the printed web as it is 30 delivered by the press, a novel inking mechanism which is simple, inexpensive and easily adjusted, the provision of a press of relatively small and 35 inexpensive construction capable of producing a relatively large product. Still another object is 40 the provision of a combined printing press and folding mechanism with means for driving the printing press or folder either separately or con- 45 jointly.

In the illustrative embodiment of the present 35 invention, a web roll of paper to be printed is supported at one side of one end of the press and means are provided for maintaining the tension 40 of the web substantially constant as it is fed from the web roll to the press. The printing press 45 comprises a bed and cylinder press having a bed approximately twice the width of the web to be printed, and over which the web passes first in one direction and then in the opposite direction parallel to its first run.

The impression cylinder is likewise of a width 50 approximately twice that of the web and is bodily moved in timed relation with the operation of the press to roll back and forth, pressing the web into contact with the printing forms sup- 55 ported on the bed as it moves in one direction and then moving back idly over the web to its initial position, thereby forming a complete impression of the two halves of the bed upon their respec- 60 tive runs of the web during each reciprocation of 65 55

the impression cylinder. The means for controlling the operative and idle movements of the impression cylinder comprise cams, secured to the impression cylinder driving means, which raise 5 and lower the impression cylinder toward and from the bed, into and out of printing position, as it is reciprocated.

Web turning means are provided at one end of the press, opposite the end at which the web 10 roll is located for guiding and optionally turning the web to position it in two side-by-side runs between the impression cylinder and bed, thereby permitting the web to be alternatively perfected or printed in two colors during a single passage 15 through the press.

The inking mechanism comprises a trough formed integrally with the bed and in which a fountain roller is rotatably mounted adapted to contact with a plurality of transferring, distributing and form inking rollers above the bed and operatively coupled with the impression cylinder reciprocating mechanism for movement therewith. Means are also provided for vibrating certain of these rollers and for freeing the 25 rollers from each other to prevent deformation of the rollers while the press is idle, and so that they may be individually rotated and are easily accessible for cleaning or other purposes. The inking mechanism is preferably separably connected with the impression cylinder so that the 30 rollers and impression cylinder may be spaced from each other for the easy removal or positioning of forms on the bed.

As the web passes through the press, it is periodically brought to rest and held stationary 35 during the actual time of printing while it is in contact with the form on the bed, and means are provided for alternately paying out and taking up slack in the web both between the web roll 40 and form and between the form and delivery mechanism. This web equalizing mechanism, as embodied, comprises a single roller mounted in oscillatable arms and over which the web is looped on both its runs and means are provided 45 for oscillating said arms in timed relation to the operation of the press.

The web, either printed in multi-color or perfected, may be cut into sheets and fed to the folding mechanism, or alternatively, the printed 50 or perfected web may be fed to a rewinding mechanism without cutting. The printed web may also be slit and one portion cut into sheets while the other portion is rewound into a roll. The rewinding mechanism rewinds the printed or 55 perfected web into a web roll and the full rewound rolls may be rotatably mounted in a supporting frame, detachably mounted above the bed of the press.

Means are provided for storing and rotatably 60 supporting one or a plurality of rewound printed or perfected web rolls, and the printed or perfected webs from these new wound rolls may thereafter be fed to the cutting means where they may be associated with a newly printed web 65 as it is delivered from the press to the cutting means. By this mechanism, the newly printed web may be associated with a previously printed or perfected, and rewound web and the associated webs are simultaneously cut in register 70 and then forwarded to the folding mechanism to form single products, each composed of sheets cut from the plurality of webs.

In accordance with the present embodiment 75 of the invention, the folding mechanism comprises three successive folding devices or units,

each comprising a pair of folding rollers and a cooperating blade to tuck the sheets to be folded between the folding rollers along the line of fold. The first pair of folding rollers and cooperating blade preferably extends substantially longitudinally and centrally of the web, being adapted to fold the cut sheet or associated sheets as they are delivered from the press. The second folding device has its blade arranged at right angles to the first, and the third blade is arranged parallel to the first blade. 10

Suitable feeding tapes are provided for feeding the sheets to folding position from the press and from the folding rollers as the sheets are passed through the folding mechanism, and stops 15 are provided for properly registering the sheets to insure proper positioning of the line of fold. Guiding means are provided between the first and second and between the second and third folding units, and that between the second and third is 20 preferably formed with a switch by which the twice-folded sheets may be delivered without further folding. The stops for the first and second folding unit are also preferably removable so that the sheets may be delivered either without folding or with only a single fold. 25

Feed boards are provided adjacent to the feeding-in position for the first and second folding units and adjacent to the first folding blade so that one full and/or one or two half size sheets 30 may be manually or automatically fed as inserts and thereafter folded in with the sheets being cut and delivered from the press. Conveyor and stacker mechanisms are also provided for receiving the folded products as they are delivered 35 from the folding mechanism. As embodied, all of the folding blades are actuated by means of a single set of cams driven from the press-driving unit, and these operate in timed relation to the 40 operation of the press.

Means are provided for driving the printing press and folding mechanism from a single motor through variable speed gearing under control of a power clutch so that the press and folder may be connected and disconnected from 45 the driving unit at the will of the operator. Means are also provided for selectively silencing the press and also the folder so that either the 50 press or folder may be driven without driving the other.

It will be understood that the foregoing general description and the following detailed description as well are exemplary and explanatory of the invention but are not restrictive thereof.

Referring now in detail to the illustrative embodiment of the present invention as shown by the accompanying drawings, means are provided for rotatably supporting a web roll of paper from which the web to be printed is unwound and fed to the press. As embodied (Figs. 6 and 7) a pair 55 of frame members 20 and 21 extend from one end of the press and are formed with suitable journals 22 to receive the web roll shaft 23 and freely support web roll 24 thereby. Collars 25 are provided near the ends of the shaft and closely adjacent to frames 20 for maintaining correct side register of the web by limiting the endwise movement of shaft 23.

The web tension control means, for maintaining the tension of the web substantially constant 70 as it is fed to the printing press comprises a pilot roller moved by changes in the tension of the web as it is drawn from the web roll, and co-operating braking members actuated by the pilot roller and controlling the rotation of the web 75

roll. As embodied, pilot roller 30 is freely rotatable in arms 31, 31', which are secured to and pivotally mounted by a shaft 32 extending between and journalled in supporting frames 20, 21. The web W is looped over roller 30 intermediate the web roll and a freely rotatable guide roller 33 journalled at its ends in frames 20, 21.

One or both of the pilot roller supporting arms 31, 31', is formed with an extension 34 upon which is slidably mounted a weight 35, which may be moved toward and from shaft 32 to vary the force applied to roller 30 and tending to enlarge the loop in the web. Weight 35 is secured in the desired position by set screw 36 projecting 15 through weight 35 and into contact with extension 34.

At one of its ends, web roll supporting shaft 23 is provided with a brake drum 38, fast on said shaft and cooperating with an arcuate brake shoe 39 pivotally mounted on stub shaft 40 projecting outwardly from frame member 21. A relatively long lever 41, also pivoted on shaft 40, serves to transmit the movements of pilot roller 30 to the arcuate brake shoe 39. Lever 41 is 25 provided with a flat face 42 on its under side and near one end adapted to contact with a pin 43 extending from the end of and positioned eccentrically with respect to shaft 32. At its pivoted end, lever 41 is provided with a downwardly extending portion 45 to contact with the end of a threaded member 46 threaded into a downwardly-extending portion 47 of the arcuate brake shoe 39.

Threaded member 46 is provided with a hand wheel 48 by which it may be turned to vary the relative position of brake shoe 39 and lever 41. A spring 49 is tensioned between lever 41 and a lug 50 on frame 21 and serves to maintain the flat surface 42 of lever 41 in contact with eccentric pin 43.

When the tension of the web W, as it is fed to the press from the web roll, is increased, roller 30 is raised against the pressure of weight 35 and spring 49, thereby lifting lever 41 and decreasing the pressure between the braking elements 38 and 39. Similarly, a decrease in the web tension permits the pilot roller 30 to be lowered and the weight of lever 41, combined with spring tension exerted by spring 49, increases the braking pressure between the braking elements.

In actual operation, the pilot roller 30 is balanced against the web tension at such a point that the web tension is maintained substantially constant, while the web tension may be increased or diminished by movement of weight 35 on extension 34 and also by varying the relative position of shoe 39 and lever 41, although threaded member 46 is used principally to compensate for 60 wear of the brake shoe.

As embodied, the bed and cylinder printing press of the present invention comprises a horizontal bed adapted to support two side-by-side forms, each approximately the full width of the web to be printed, and an impression cylinder adapted to be rolled back and forth over the forms and to press the web into impression contact therewith. The bed comprises a flat, horizontal casting 60 supported between the side frames of the press 61 and provided with a pair of spaced apart transversely-extending raised lips 62 between which the two chases 63 containing forms 64 may be locked by means of furniture and quoins (not shown). The upper 75 face of bed 60 is planed flat over that portion

to receive the chases 63. One of forms 64 comprises the matter to be printed on one side, while the other form may be for the other side or a second color for the first side of the web.

The impression cylinder comprises a rigid cylindrical member 70 of a length slightly in excess of twice the width of the web to be printed and provided with the usual packing. Impression cylinder 70 is rotatably mounted at each end of its shaft 71 by eccentrics 72 which are partially 10 rotatable in side frames 73 of the impression cylinder carriage. Cylinder 70 has its axis parallel to the plane of bed 60 and is adapted to be moved toward and away from the bed 60 and forms 64 for its printing and non-printing movement over the bed.

The impression cylinder carriage on its lower portion is provided with guides to cooperate with the upper and lower guideways 75 on each side of the bed to hold the carriage against vertical 20 and transverse movement as the carriage is moved back and forth over the bed. Guides 75 are preferably formed integral with the side frames 61 and extend parallel to each other and to the plane of bed 60.

Means are provided for rotating impression cylinder 70 as it is rolled back and forth over the form-supporting bed and for this purpose is provided with gears 78 at its ends which mesh with racks 79 extending parallel to guideways 75 30 and along the sides of the bed. Means are provided for reciprocating the impression cylinder carriage and, as embodied, a gear 80 and fly wheel 81, on opposite sides of the press, are rotatably mounted by means of shaft 82, journalled 35 in the side frames 61, with both said gear and fly wheel keyed to said shaft. Both sides of the impression cylinder carriage are operatively connected with said gear and fly wheel by means of pitmans 84, connected between crank pins 85 and 40 pins 86 at the sides of the impression cylinder carriage. As gear 80 and fly wheel 81 rotate, the sliding carriage 88, supporting the impression cylinder, is reciprocated back and forth throughout the length of the forms supported on 45 the bed.

Means are provided for raising and lowering the impression cylinder into and out of contact with the forms. For this purpose eccentrics 72, at each end of the impression cylinder, are oscillated in timed relation with the reciprocation of the carriage, so that the impression cylinder is lowered to press the web of paper into printing contact with the form as the carriage and impression cylinder are moved towards the shaft 55 82 and to raise the impression cylinder out of contact with the form on the return stroke of the carriage. As embodied, cams 90 are provided at each end of the impression cylinder and mounted on, or formed integrally with, pitmans 60 84, and coact with cam rollers 91 mounted on plates 92 secured to their respective eccentrics 72. Each cam 90 is mounted near the carriage end of its pitman 84 and is provided with a cam slot comprising two arcuate portions 95 and 96, 65 each concentric with pin 86, and connected together by a connecting slot 97 which is eccentric with reference to pin 86. Slots 95 and 96 and the connecting portion 97 are of uniform width, approximately equal to the diameter of cam 70 roller 91.

With pitman 84 at the end of its stroke, the parts are in the position shown in Figure 9 of the drawings. Rotation of the driving gear and fly wheel elevates the pitman 84 and moves 75

cams 90 to a position where the cam rollers 91 are within portions 96 of the cam slots. This movement lowers the impression cylinder into printing position and holds it in that position until cam roller 91 is moved to the connecting portion 97 of the cam slot at the other end of the pitman stroke. On the return movement of the carriage roller 91 rides in the outer concentric portion 95 of the cam slot and maintains the impression cylinder out of printing contact with the web, but not sufficiently out of contact to disengage gear 78 and its driving rack 79.

The impression cylinder carriage is preferably formed in two separable portions, one of which carries the impression cylinder, as just described, while the other carries the inking mechanism. This second portion of the carriage 100, carrying the inking mechanism, is preferably formed as a continuation of the carriage 88. Carriage 100 is provided with guides, shaped similarly to those of carriage 88, and cooperating with guideways 75. The abutting machined portions of the parts 88 and 100 are held together by means of bolt 102, threaded into head 88 and held against unscrewing by pin 103. Bolt 102 passes through the carriage portion 100 and holds it by nut 104. By removing nut 104, the carriage portion 88 may be moved independently of the portion 100 and they may be separated and spaced apart as shown in Figure 12. In this position, the operator has full access to the bed 60 and the chases 63 supported thereon, thereby facilitating the positioning or removal of the forms, or their correction.

Means are provided for guiding the web from the web roll through the press in two side-by-side, oppositely directed runs and with either side of the web adjacent to the form on its second passage through the press, and from the press to the delivery mechanism.

As embodied, the web W is fed from the web roll 24 to guide roller 33, being looped around a small cylinder 160 of a width substantially the same as that of the web and fixed on the shaft 82, and is held against cylinder 160 by means of feeding tapes 161. After guide roller 33 the web passes between the feeding cylinder 160 and feeding tapes 161 and thence over guide roller 162 to guide roller 163, and is looped around an equalizing roller 164, which will be described more in detail. The web then passes over guide roller 166, under impression cylinder 70, and then over a guide roller 167 also freely rotatable and supported on a forwardly-projecting arm 168 on carriage 88.

Web turning and guiding means are provided at the end of the press for turning and guiding the web to a position parallel to and alongside of the first run of the web. For this purpose a pair of turner bars 170, 171 are mounted on the press frame and cooperate with a guide roller 172 to transfer the web to this side-by-side position. The turner bar 170 is reversably positioned at the end of the press frame and may be moved to a position at right angles to bar 171, or may be secured in a position parallel to bar 171. The guide roller 174 is rotatably mounted in the press frame at one end of the press and closely adjacent to turner bar 173 and extends parallel to the run of the web. When it is desired to perfect the web, roller 174 need not be employed and turner bar 170 is positioned parallel to bar 171. With the parts in this position, and as shown by Figure 2, the web is first passed through the press and printed on one side, and is again passed through the press with the printed side upper-

most or away from the form. When it is desired to print in two colors on the web with one of forms 64 carrying the matter for one color, while the other form carries the matter for the other color, the web is passed over turner bar 170, positioned at right angles to turner bar 171, is run over guide roller 174 then turner bar 171 and guide roller 172, placing the once printed side of the web on the under side or adjacent to the form.

After passing roller guide roller 172, the printed and turned web passes over guide 176 to guide roller 167, under impression cylinder 70, over guide roller 166 and to guide roller 178 after looping around equalizing roller 164. After roller 178, the web may be led either to the rewinding mechanism or to the cutting, folding and delivering mechanism.

Guide rollers 163, 165, 166 and 167 extend across the entire width of the press or slightly more than twice the width of a single web, and are each divided into longitudinal halves which may be reversely rotated. Roller 162 need extend only one half the width of the press and is positioned on the side of the unprinted web, while rollers 172, 176 and 178, also of single web width, are positioned on the delivery side or the return run of the web. Equalizing roller 164 may be a single roller extending across the entire width of the press inasmuch as the two runs of the web move in the same direction as they pass around it.

In the operation of a bed and cylinder printing press, the web is stopped during the entire time it is in contact with the printing form, as there can be no relative movement between the web and form during the time of the impression. In accordance with the present invention, means are provided for taking up the slack in and paying out an accumulated surplus in the web during this impression interval so that the speed at which the web is unwound from the web roll and is delivered to the delivery mechanism may remain constant.

As embodied, means are provided between the web roll and impression cylinder and between the impression cylinder and the delivery and folding cylinder for concomitantly taking up slack in the web at one of these points and dissipating the slack at the other, and vice versa. Equalizing roller 164 is freely rotatably journaled in arms 180 which are oscillatably mounted at the ends of the roller and the sides of the press by means of shaft 181 rotatably journaled in the side frames 61. A spring 182 coiled about shaft 181 and having one of its ends fastened to said shaft and the other fastened to the frame is provided for moving the arms 180 and roller 164 forwardly of the press, while cam means are provided for controlling the motion of this roller in timed relation with the operation of the press. Cam 184 is rotatably mounted on shaft 185, to which it is keyed and is driven by gear 186 meshing with gear 187 on the main shaft 82. The cam roller 188, rotatably mounted at the end of link 189, is adapted to contact with the periphery of cam 184. Link 189 is formed with a slotted yoke, fitted over shaft 185 by which the link is supported, and at its other end, link 189 is pivotally connected with arm 180 by means of pivot pin 190.

The action of cam 184, and roller 164 bodily moved thereby, is to provide a surplus of web which is gradually payed out as the web is stopped during printing, continuing this paying out and at the same time taking up the slack in the twice printed web, and then during the idle

stroke of the impression cylinder to gradually pay out the accumulated surplus in the unprinted web while the slack is being taken up in the twice printed web. By properly designing the shape of 5 cam 184 with reference to the time of impression, the web speed and the position and size of the various parts, the speed of the web being fed from the web roll and being delivered to the cutting and folding mechanism may be rendered constant, notwithstanding the fact that the web is 10 completely stopped at points over the form in both its runs and at the turning bars.

As the printed web is delivered from the point of impression over guide roller 166, equalizer 15 roller 164 and guide roller 178, it is fed alternatively to the web rewinding mechanism or the cutting and folding mechanism, and optionally operable slitting means are provided for permitting 20 one longitudinal half or portion of the web to be rewound while the other longitudinal half is cut and folded. A slitting disc 192 is provided adjacent to guide roller 178 and cooperates therewith to slit the web when this is desired.

As embodied, the rewinding mechanism comprises 25 a pair of closely adjacent and parallel rollers 200, rotatable in suitable journals formed in the detachable frame members 201 and 202, positioned above the main shaft 82, and securely fastened to the side frames of the press. Rollers 30 200 are driven by suitable gearing from cylinder 212. A series of belts 203 are mounted adjacent to one of the rollers 200 and are driven at web speed by the press, while the printed web passes from guide roller 178 over guide roller 204 and 35 is fed along and pressed into contact with roller 200 by means of belts 203. The leading end of this web W is attached to a core supported on rollers 200 and the web is rewound to form a roll.

A vertical slot 206 is provided between the 40 frame members 201 and 202, at each side of the press, and a web roll shaft, projecting through the axis of the rewinding roll 208, may project through these slots to steady the roll.

Figure 5 of the drawings illustrates the printed 45 web being fed to the cutting cylinder and folded. As shown, the web is led from guide roller 178 to guide roller 210 from which it is passed into contact with cutting cylinders 212 and pressed thereagainst by driven belts 213. Cutting cylinder 50 212 cooperates with a cutting cylinder 214 fixed on main shaft 82, one of said cylinders being provided with a cutting knife while the other is provided with a cutting block. Cylinders 212, 214 and 160 are preferably of a circumference 55 equal to a single page length cylinders 160 and 214 being both fixed on shaft 82 and rotating together. The web passes between cylinders 212 and 214, each of approximately the same width as the web, and is thereby cut into sheet lengths 60 to form one sheet at each revolution of the cylinder. The sheets delivered from between cylinders 212 and 214 are fed between stationary guides 216, 217 which direct the sheets between press driven tapes 218, 219, preferably driven at 65 web speed, which tapes convey the sheets to the folding mechanism, as will later be described in detail.

When slitter 192 is employed, one half of the 70 printed web is directed along the path shown in Figure 1 to the rewinding mechanism, while the other half is directed along the path shown in Figure 5 to the cutting and folding mechanism.

Means are provided for storing a plurality of 75 printed and rewound web rolls so that the printer may print a plurality of webs each with different

forms, and later associate these webs to form a product comprising sheets from a plurality of webs. As embodied, a supplementary frame is provided above the press and comprises a pair of generally triangular frame members 220, one 5 at each side of the press, and supported on frames 202. The upper portions of frames 201, 202 and 220 form together a pair of substantially horizontal tracks, one at each side of the press, extending on both sides of vertical slot 206. 10

At the ends of these tracks are provided depressed, open-top journals to receive the web roll shafts for the rewound rolls and thereby rotatably support the rewound rolls so that the previously printed and rewound webs may be fed to 15 the cutting and folding mechanism and be associated with the web being printed. As embodied, tracks 222 extend horizontally for a distance slightly greater than the diameter of a web roll and are adapted to receive web roll shafts 20 in the open journals 223 and 224 at each end of the web roll.

Means are also provided for lifting the completely rewound web roll off from rollers 200 and 25 on to tracks 222 and for this purpose, pulleys 226, at each end of the web roll, are rotatably mounted on the upper portion of frames 201. Cables 227 pass over said pulleys and at one end, each is provided with a hook 228 adapted to hang in line with slot 206. The other end of each cable is 30 connected to a drum 229 rotatably journaled on a shaft in frame 201 and extending transversely between the frames, and may be rotated, to wind or unwind the cables, by means of worm 230 connected to handle 231 and also rotatably journaled in one of the frame members 201. As soon as the web roll has been fully rewound, the hooks 228 are fitted over the web roll shaft at their respective ends of the web roll, handle 231 is rotated to raise the roll to the level of tracks 222 35 and the roll may then be swung to the left or right (Fig. 4) and then rolled to the corresponding end of the track.

Web tension means are provided for tensioning 40 the previously printed webs as they are fed from the rewound web rolls to be associated with the webs being printed. For this purpose, the web roll shafts are provided with brake drums 234, fast with respect to their respective web rolls, and 45 cooperating with a brake shoe 235 pivotally mounted on the frame member 201 or 220. Each brake shoe arm is provided with an extension 236, notched to receive and support a weight 237 which 50 may be moved toward and from the brake shoe pivot to vary the pressure between the brake shoe 55 and drum.

Figure 5 of the drawings illustrates the operation 55 of the mechanism with a printed web being associated with a plurality of previously printed and rewound webs 208. In such a run, the web 60 being printed is fed directly from guide roller 178 to guide roller 210 and thence to the cutting cylinders 212, 214 and folding mechanism. The web from one or more rewound rolls 208 is led over 65 guide roller 204 and is fed along by tapes 203 to guide roller 210 where the rewound webs are 70 associated with the web being printed. The associated webs are fed between cutting cylinders 212, 214 and the sheets cut from the associated webs are fed between guides 216, 217 to a position between tapes 218 and 219 which forward them to the folder.

Any of the webs may be printed in two colors or may be perfected in one color, and any of these webs may be a full or partial width web, 75

with the result that an exceedingly wide variety of products may be produced by various combinations of these factors.

Referring now in detail to the present embodiment of the folding mechanism as illustrated in Figures 13 to 20 of the drawings, the folding mechanism as a whole is positioned at the delivery end of the printing press and to one side of the web roll, and is provided with guides 250 mounted 10 on the folding mechanism and between which the cut sheets are fed from the press by delivery tapes 218, 219.

The folding mechanism comprises three oscillating blade folders, each successive folder being 15 disposed at right angles to the preceding folder, and means are provided whereby manually fed insets or onsets may be fed to the folder so as to be folded with the printed sheet. The first folder includes rollers 252, blade 260 and feeding tapes 20 290 and 291 driven by pulleys 292 and 295. The second folder includes blade 278 on arm 279 and shaft 280 and rollers 278 and 271. The third folder includes rollers 286, blade 285, tapes 308 and 25 309 driven by pulleys 310 and 311 and guides 318, 319 and 331. Guide 319 is removable so that twice folded sheets may be delivered directly to belts 326 or may be stacked in stacker 333. Additional full sheets may be fed from feed board 341, and other insets or onsets may be fed to any of the 30 folding devices. Folding rollers 252, 270, 271, 280, blades 260, 278 and 285, and tapes 290, 291, 308 and 309 are all driven from the press driving motor through chain 426.

The main folder driving shaft 355 is driven 35 from the driving unit, as will be later described, and shaft 355 carries a series of cams by which the several folding blades, delivery belts and stacker are operated.

As embodied, the driving mechanism for alternatively or conjointly driving the printing press and folding mechanism comprises a driving electric motor 400 slidably mounted upon its base plate 401 and movable therewith by means of a threaded member 402 secured to the base 401 45 against axial movement and cooperating with a threaded aperture on the lower portion of the motor 400.

On the motor shaft 404 is mounted a V-pulley 405, of conventional construction and variable effective diameter, to drive the free wheel 406 of 50 clutch 407 through the V-belt 408. By varying the distance between the two conical members of pulley 405 and by variably positioning the motor 400 on its base, the driving ratio and the speed 55 of wheel 406 may be varied to vary the speed of operation of the press.

Wheel 406 is freely rotatable on shaft 410 which is rotatably journaled in floor brackets 411 and may be placed in driving relation thereto by 60 means of clutch 407. Shaft 410 is provided with a longitudinally slidable pinion 412, held in the desired position by set screw 413 in mesh with gear 414 pinned to shaft 415 which shaft is rotatably journaled in frame 61 and journal bracket 416. Shaft 415 also carries a pinion 417 meshing with bull gear 80 on shaft 82.

At its other end shaft 410 carries a longitudinally slidable pinion 420, slidable keyed to said shaft and held in desired axial position by set 70 screw 421 and meshing with gear 422 rotatably mounted by shaft 423 which is journaled in floor brackets 424. Shaft 423 also carries sprocket 425 which drives flexible chain 426 running over sprockets 425 and the main folder driving sprocket 427 on the folder main shaft 355.

The clutch-operating means comprises a hand lever 430 pivotally mounted between brackets 431 at one side of the press and connected with rod 433 slidable in the side frame 61. Rod 433 is connected with shipper lever 434 by means of pin and slot connection 435, and lever 434 is also connected with the clutch collar by pin and slot connection 436. Shipper lever 434 is pivoted at 438 and provided with a braking surface 439 to bear against a brake disc 440.

With the hand-operating lever 430 in the position shown in Figure 22, the clutch is engaged and motor 400 is operatively connected with both the press and folder to drive them in timed relation to each other. When it is desired to operate only 15 the press, as in rewinding, the pinion 412 remains in mesh with pinion 414, but pinion 420 is slid out of engagement with gear 422. Similarly, when it is desired to drive the folder, without driving the press, as in folding a rewound web or operating the folder as a job folder, the pinion 420 is placed in mesh with gear 422 and pinion 412 is slid out of mesh with gear 414. With either of these optional drives, the operation of the clutch remains the same and by movement of lever 430 25 the press or folder may be driven from motor 400 or quickly stopped by the application of pressure between brake members 439, 440.

As will be understood from the foregoing description, the present invention provides a combined bed and cylinder printing press and folder, having unusual flexibility, by which a very wide range of sizes of products may be produced. As an illustration of the extremely wide range of 30 products which may be produced by the present 35 embodiment, it being understood that this illustration is in no wise restrictive of the invention, it may be said that the products may comprise a minimum of one-half full-size sheets each, or four pages of a thrice-folded sheet and may be increased in size by small increments to the maximum product of 80 pages with thrice folded sheets.

More in detail, the unfolded product may comprise a half sheet, a full size sheet, one and a half, two, two and a half or three sheets, any or all of which may be perfected, multi-color or perfected in different colors. This product may be delivered unfolded or folded, if desired, once, twice or three times and may be increased in size, if desired, by 50 the addition of one full sheet and/or one or two half size sheets, as inserts. These inserts, of course, may be printed in any desired manner. That is, the product as delivered from the press may comprise: Two to eight pages of full sheet 55 size, with a two page minimum increment in the size of the product. Two to twenty pages of half sheet size with a two page minimum increment in the size of the product. Four to forty pages of quarter sheet size with a four page 60 minimum increment in the size of the product. Eight to eighty pages of eighth sheet size with an eight page minimum increment in the size of the product. In any of said products, any of the sheets cut from the web may be multi-color, perfected, or perfected in different colors, and the inserts may be printed in any desired manner.

The invention in its broader aspects is not limited to the specific mechanisms shown and described but departures may be made therefrom within the scope of the accompanying claims without departing from the principles of the invention and without sacrificing its chief advantages.

What I claim is:—

1. In a web fed printing press, a web feeding cylinder and a web cutting cylinder, said cylinders being of equal diameter and mounted on a single shaft, and means for directing two web reaches to said cylinders whereby one reach is forwarded and the other reach is cut into sheets. 5
2. In a web fed printing press, a web feeding cylinder and a web cutting cylinder, said cylinders being of equal diameter, closely adjacent to each other and axially alined, and means for directing two web reaches to said cylinders whereby one reach is forwarded and the other reach is cut into sheets. 10
3. In a printing press, the combination of means for rotatably supporting a rewound web roll, means for rewinding a printed web into a roll and means for transferring the rewound roll from rewinding to feeding position to permit the winding of a second printed web roll by said rewinding means. 15
4. In a printing press, the combination of means for rotatably supporting a rewound web roll in feeding position, means for rewinding a printed web into a roll, said rewinding and supporting means being positionally related to each other so that the rewinding and feeding positions of a full roll are substantially the same and means for transferring the rewound roll from rewinding 20 to feeding position. 25
5. In combination, a web fed printing press, means for longitudinally slitting the web as it is delivered from the press, means for cutting one portion of the web into sheets and means for rewinding another portion of said web, a folder and means for forwarding the cut sheets thereto. 30
6. In combination, a web fed printing press, means for longitudinally slitting the web as it is delivered from the press, means for cutting the web into sheets, means for optionally rewinding a portion of the web, means for rotatably supporting the rewound web roll and means for guiding the rewound web to the cutting means, a folder and means for forwarding the cut sheets thereto. 35
7. In combination, a web fed printing press, means for longitudinally slitting the web as it is delivered from the press, means for cutting the web into sheets, alternatively operable means for rewinding a half web or a full width web and means for rotatably supporting the rewound web roll and guiding means for guiding the rewound web to the cutting means. 40
8. In a web printing press, the combination of means for printing a web, means for cutting the web into sheets, means for alternatively rewinding the web, means for rotatably supporting the rewound web roll, means for associating the rewound web with a second web being printed in advance of the cutting means, means for folding the associated sheets cut from said webs and feeding means for insetting a sheet prior to folding. 45
9. In a web fed printing press, the combination of a form supporting bed and impression cylinder, means for guiding the web between said bed and cylinder in opposite directions in side-by-side runs to twice print the web, a bodily movable roller around which the unprinted and twice printed web is looped and press-driven cam means for bodily moving said roller. 50
10. In a web fed bed and cylinder printing press, the combination of a web roll support, sheet delivery means at the side of said support, web turning means between which and the support and delivery means the bed and cylinder are posi- 55
- tioned, a roller extending transversely of the web and around which the printed and unprinted runs of the web are looped and press-driven cam means for bodily moving said roller. 60
11. A printing press including in combination a, form-supporting bed and cooperating inking and impression members, a web supply means and cutting means at one end of and close to the bed for cutting the web into unfolded sheets, and web turning means at the other end of the bed. 65
12. In a printing press, the combination of a form supporting bed and impression member, means for guiding the web between said bed and member in opposite directions to print the web twice and a bodily movable roller around which the unprinted and twice printed web is looped. 70
13. In a printing press, the combination of a form supporting bed and impression member, means for guiding the web between said bed and member in opposite directions to print the web twice and a bodily movable roller around which the web is twice looped, once on the unprinted portion and once on the twice printed portion, said loops opening away from the roller in different directions. 75
14. In a printing press, the combination of a form supporting bed and impression member, means for guiding the web between said bed and member in opposite directions to print the web twice and a bodily movable roller mounted in 30 oscillatable arms and around which roller the web is twice looped, once on the unprinted portion and once on the twice printed portion, said loops opening away from the roller in different direc- 80
15. In combination, a stationary bed and traveling cylinder web perfecting press, a cut sheet folding machine, and means for assembling and inserting a previously printed sheet with the product being produced by the press while said press and folder are working in unison. 85
16. In combination, a stationary bed and traveling cylinder web perfecting press, a cut sheet folding machine, means for assembling and inserting a previously printed sheet with the product being produced by the press and means for delivering the assembled product flat or folded. 90
17. A flat bed web perfecting press in combination with a device for severing a web into sheets and a hand fed cut sheet folding machine, means for rewinding a web in the press after being printed and means for feeding a web to the severing device to be cut in sheets and delivered to the folding machine and means whereby a sheet can be manually fed into association with a sheet cut from the web to be folded and delivered as one product. 95
18. A bed and cylinder printing press including in combination a double width bed and cylinder having two side by side forms, inking mechanism, a web supply and means for feeding a web in both directions and over both forms to perfect the web, web rewinding means and sheet cutting means receiving the web from the perfecting half of the bed and a slitter for slitting the perfected web and means for optionally directing a half web to the rewinding means and the other half to the sheet cutter. 100
19. A bed and cylinder printing press including in combination a double width bed and cylinder having two side by side forms, a web supply and means for feeding a web in both directions and over both forms to perfect the web, rotary means coacting with the incoming web to feed it toward the bed and having sheet cutting means for 105

cutting sheets from the perfected form coming from the bed.

20. A bed and cylinder printing press including in combination a double width bed and cylinder having two side by side forms to perfect the web, a web supply and means for feeding a web in both directions and over both forms, web rewinding means and sheet cutting means substantially in line with the perfecting bed, and 10 means for optionally directing the printed web either to the rewinding means or direct to the sheet cutting means.

21. A bed and cylinder printing press including in combination a perfecting bed and cylinder, 15 inking mechanism, a web supply and means for feeding the web through the printing mechanism, sheet cutting means closely adjacent the perfecting end of the printing mechanism and receiving the web directly therefrom, web rewinding 20 means adjacent thereto, means for moving a rewound web to unwinding position, and means for associating the rewound web with a newly printed web and feeding the associated webs directly to said cutting means.

22. A bed and cylinder printing press including in combination a perfecting bed and cylinder, inking mechanism, a web supply and means for feeding the web through the printing mechanism, sheet cutting means closely adjacent the perfecting 30 end of the printing mechanism and receiving the web directly therefrom, web rewinding means adjacent thereto including unwinding supports, means for moving a rewound web to unwinding position, and means for associating a plurality 35 of rewound webs and feeding them to said sheet cutting means, and for optionally associating a freshly printed web with them prior to cutting.

23. A printing press including in combination a traveling cylinder, side by side beds for perfecting a web, a web supply roll at one end of one 40 of said beds, web equalizing means between the supply roll and said bed, turning means at the opposite end for turning the web and directing it over the second bed, cutting means at the end

of the second bed, optionally usable web rewinding means adjacent said cutting means, flat sheet-folding means alongside the web supply means, and means for directing sheets from said cutting means to said folding means. 5

24. A printing press including in combination a traveling cylinder, side by side beds for perfecting a web, a web supply roll at one end of one of said beds, web equalizing means between the supply roll and said bed, turning means at the 10 opposite end for turning the web and directing it over the second bed, cutting means at the end of the second bed, and means for receiving the sheets and folding them perpendicularly to the cut edges. 15

25. A printing press including in combination a traveling cylinder, side by side beds for perfecting a web, a web supply roll at one end of one of said beds, web equalizing means between the supply roll and said bed, turning means at the 20 opposite end for turning the web and directing it over the second bed, cutting means at the end of the second bed, and means for receiving the sheets and folding them both perpendicularly 25 and parallel to the cut edges.

26. A printing press including in combination two type beds side by side for perfecting a web, a traveling impression cylinder, means for supplying a web to the first bed, means at the opposite end of the bed for turning the web and directing it to the second bed, and a web equalizing roller over which the fresh web and the perfected web run side by side and in opposite directions. 30

27. A printing press including in combination two type beds side by side for perfecting a web, 35 a traveling impression cylinder, two cylinders side by side at one end of the bed, one feeding a web to the bed and one cutting perfected sheets, means at the opposite end of the bed for turning the web and directing it parallel to itself in a reverse direction and means for folding the sheets perpendicular to the cut edges. 40

PAUL F. COX.
